M. CHEW.

APPARATUS FOR PRODUCING FIBER BOARD.

APPLICATION FILED OCT. 23, 1920.

1,423,082.

Patented July 18, 1922.

UNITED STATES PATENT OFFICE.

MANLEY CHEW, OF MIDLAND, ONTARIO, CANADA.

APPARATUS FOR PRODUCING FIBER BOARD.

1,423,082.

Specification of Letters Patent. Patented July 18, 1922.

Application filed October 23, 1920. Serial No. 419,050.

To all whom it may concern:

Be it known that I, MANLEY CHEW, of the town of Midland, in the county of Simcoe, Province of Ontario, Canada, have invented certain new and useful Improvements in Apparatus for Producing Fiber Board, of which the following is the specification.

My invention relates to certain new and useful apparatus for producing fiber board by a method forming the subject matter of a separate application in which the chip waste from saw mills is utilized.

The object of the invention is to provide such apparatus that the board may be produced at the smallest possible expense and necessarily also with a minimum amount of labor and attention to my apparatus by which the method is carried out.

The drawing represents the apparatus for carrying out my method.

1 is a container of any convenient size having steam pipes 2 contained in the bottom thereof. This container 1 is filled with chip waste by a suitable conveyer such as is frequently used in saw mills, then water is introduced into the waste. The heat applied to the steam pipes serves to convert the water into steam, which permeates the mass of waste.

20 The mass of waste is cooked from ten to twenty-four hours depending upon the nature thereof. The steam of course passes through the waste and softens and renders it pliable and workable. Water is then introduced into the mass and it is then fed by any suitable means to a hopper 3 from whence it is conveyed by a endless chain of buckets 4 to a hopper 5 at the top of a beater 6, or series of beaters. The beater I use is the Claflin beater, although other forms of beaters may be employed.

45 The water introduced into the mass more or less floats the waste and converts it into a rough pulplike watery condition. In the beaters the mass is so treated that the fibers are separated into very fine strands, shredded yet pulplike in form.

From the beater 6 the pulp is passed by a spout 7 to a spout 8 which conveys it into the cylindrical screening machine 9, and into the cylindrical mesh screen 10 thereof. The pulp which passes through the screen 10 is conveyed by means of a pipe 11 to a receptacle 12. The pulp which does not pass

through the screen 10, that is, the tailings, 55 pass through a pipe 13 to a ball or roller mill 14 where it is rendered sufficiently fine to be fed by the pipe 15 to the feed pipe 11. Instead of the beater 6, a ball or roller mill may be advantageously substituted.

60 16 is a cylindrical woven wire screen against which the pulp in the receptacle 12 impinges and 17 is a felt roll by which the pulp is carried off from the cylindrical screen in the form of long strips of fine 65 shredded pulp. Water is again introduced by the pipes 18 and 19 to cause a free flow of the pulp on to and down the chute 20 into the vat 21.

From the vat 21 a pipe 22 extends to the 70 pump 23 whereby the pulp is elevated and pumped by a pipe 24 into the agitating tank 25 which contains a series of rotary agitators 26 of any desired form such as shown in the drawing with paddles 27.

75 By means of the rotary agitators the pulp is kept at a proper and uniform consistency in the agitating tank or vat 25. From the agitating tank the pulp is carried by means of a pipe 27*, pump 28, and pipe 29 into a 80 boxlike receptacle 30 having an intermediate bottom 30*. The pulp passes in a stream, in the course indicated by arrow, being interrupted in its flow by slats 31 on the intermediate bottom and slats 32 on the actual 85 bottom. These slats form obstructions so as to catch any heavy foreign matter such as metal.

85 After the stream passes over the slats the pulpy mass passes along and is precipitated 90 or projected along down a flat chute of substantially a width corresponding to the length of the fiber board. The pulp is fed at such a speed as will induce the filmy mass of pulp to feed over the entire width of the chute 95 in its passage to the press, 33 which is preferably a hydraulic one.

95 In the press the water is expressed from the pulp, and is formed up into a solid board.

100 From the press the boards are stacked into kilns and dried.

105 After being thoroughly dried they are treated with a waterproofing liquid or composition.

In describing my apparatus I desire it to be understood that I do not wish to limit myself to the exact types of machines form-

ing the various parts of the apparatus as various changes may be made therein without departing from my invention.

What I claim as my invention is:

- 5 1. Apparatus for producing fiber board comprising a container, means for moistening and heating the chip waste therein, a beater, a conveyer between the container and beater, a screen, a chute extending between the beater and screen, a receptacle, a chute between the screen and receptacle, a cylindrical screen located in the receptacle, a co-acting felt roll cooperating therewith, a vat, a chute extending from the receptacle to the vat, an agitator, a pipe and pump between the vat and agitator, a final receptacle provided with cross slats located in the bottom of the receptacle, and a pipe line extending from the agitator to the final receptacle, a pump located in the pipe line, and an inclined flat chute leading from the final receptacle to the press. 35
- 10 2. Apparatus for producing fiber board comprising a container, means for moistening and heating the chip waste therein, a beater, a conveyer between the container and beater, a screen, a chute extending between the beater and screen, a receptacle, a chute between the screen and receptacle, a cylindrical screen located in the receptacle, a co-acting felt roll cooperating therewith, a vat, a chute extending from the receptacle to the vat, an agitator, a pipe and pump between the vat and agitator, a final receptacle provided with cross slats located in the bottom, and a pipe line extending from the agitator to the final receptacle, a pump located in the pipe line, and an inclined flat chute leading from the final receptacle to the press. 40
- 15 3. In the apparatus described, a receptacle interposed between the screen and the vat, a cylindrical screen located in the receptacle, a felt roll located at one side in proximity to the top of the tank co-acting with the screen and a chute leading from the vat to proximity in which the roll is located and designed to carry off the mass from the roll. 45
- 20 4. In the apparatus described, a receptacle interposed between the screen and the vat, a cylindrical screen located in the receptacle, a felt roll located at one side in proximity to the top of the tank co-acting with the screen and a chute leading from the vat to proximity in which the roll is located and designed to carry off the mass from the roll, and water pipes extending on both sides of the felt roll. 50
- 25 5. In the apparatus described, a receptacle interposed between the screen and the vat, a cylindrical screen located in the receptacle, a felt roll located at one side in proximity to the top of the tank co-acting with the screen and a chute leading from the vat to proximity in which the roll is located and designed to carry off the mass from the roll, and water pipes extending on both sides of the felt roll. 55

MANLEY CHEW.
